FRANK D. CARNEY, OF BETHLEHEM, PENNSYLVANIA.

HOLLOW INGOT AND METHOD OF MAKING SAME.

1,277,543.

Specification of Letters Patent. Patented Sept. 3, 1918.

Application filed March 23, 1918. Serial No. 224,184.

To all whom it may concern:

Be it known that I, FRANK D. CARNEY, a citizen of the United States, and a resident of Bethlehem, in the county of Northampton and State of Pennsylvania, U. S. A., have invented certain new and useful Improvements in Hollow Ingots and Methods of Making Same; and I do hereby declare the following to be a full, clear, and exact 10 description of the invention, such as will enable others skilled in the art to which it appertains to make and use the same, reference being had to the accompanying drawings, and to letters or figures of reference marked 15 thereon, which form a part of this specification.

Heretofore, in the production of the ingots cast in the customary vertical method, it has been difficult to avoid pipe, segregation, 20 surface cracks and other defects; slag inclusions resulting from reactions in the molten metal during solidification and inclusions from accidental additions of foreign matter. It is also an impossibility to 25 obtain a uniform uniaxis crystalline condition in the ingots, due to the great variation in the cooling rate from the outside surface to the center.

To avoid the above trouble when casting 30 ingots which are to be used for objects with hollow centers, I have cast cylindrical and conical ingots with a uniform cylindrical bore, by pouring the molten steel into the mold revolving at a high speed on its horizontal axis, producing, thereby, a centrifugal force in excess of the force of gravity.

I found, for example, in the case of steel 40 when poured or cast directly on the iron or steel surface of an ordinary ingot mold revolving on its horizontal axis at a speed sufficient to produce centrifugal force, that it was impossible to make an ingot free from surface defects, strains and cracks.

While the method of horizontal centrifugal casting is known in general, I believe 45 that I am the first to cast cylindrical and conical ingots of variable dimensions and weight, in a practical way which are free from the above enumerated defects.

50 My invention overcomes said defects, and is a method of casting hollow, cylindrical and conical ingots free from pipe, internal strains, surface cracks and the customary internal defects due to segregation and slag inclusions, in a practical way, by casting rapidly under the action of centrifugal

force in a suitable machine, one or a plurality of ingots from a single ladle of molten steel; controlling the relative rate of cooling of the interior and exterior surfaces 60 of the ingot; controlling the crystalline structure of the ingot, and rapidly removing the ingot with the mold from the revolving container thereof.

In order to clearly define the mode of 65 procedure, reference will be made to the accompanying drawings, in which like parts are similarly designated, and in which—

Figure 1 is a vertical longitudinal section of a machine such as I use to produce the 70 ingots referred to.

Fig. 2 is a diagrammatic plan view, and Fig. 3 an elevation of a plant for centrifugally casting the hollow ingots.

Fig. 4 is a cross section, and Fig. 5 is a longitudinal section, partly 75 in elevation, of a modification of the apparatus.

Fig. 6 is an elevation partly in longitudinal section, and Fig. 7 an end view of a modified form 80 of ingot mold, and

Fig. 8 is an elevation, partly in section, of another form of such mold.

Figs. 9 and 10 are diagrammatic views of 85 the manner of simultaneously casting a plurality of hollow ingots.

In the apparatus 1 is the carrier or drum of cast metal provided between its ends with a pair of tires or the equivalent, 2. 90 Contained within the drum is the ingot mold 3 of sheet metal. This sheet metal mold 3 is held within the carrier or drum 1 by clamps, and in the structure shown the clamps 4 at the right hand end, Fig. 1, directly engage one end of the sheet metal mold 3, while at the other end thereof is an annular, trough shaped spill way 5, of brick, Figs. 1 and 9, or of sheet metal 5^a, Fig. 10, fitting into the end of the drum 1 and engaged by the clamps 6.

These clamps are of well known construction, of angle shape and are adjustable longitudinally of the drum in slots therein.

The sheet metal molds 3 are not to make 105 continuous surface contact with the drum 1, and for this purpose they may have any desired projections, either longitudinal corrugations 3^a, as in Figs. 4 and 5, or quincunxially arranged rounded bulges or projections 3^b, Figs. 6 and 7, or more pointed projections, as 3^c, Fig. 8.

The same result can be obtained by making the interior of the carrier corrugated, with spiral or parallel ribs 1^b, as shown in Fig. 5.

- 5 When internal ribs 1^b on the carrier are used in connection with a longitudinally corrugated mold 3^a, these projections cross one another and provide an ample space for the insertion of a pulverulent or sand-like insulation of fire-proof material between the two concentric members, when it is desirable to employ such material. The dimensions of this interspace, as well as the nature of the material included in said space, 10 15 whether air, or sand, dolomite, &c., controls the rate of solidification, as with some steels it is desirable that solidification takes place quicker than with others.

Several such carriers or drums 1 with their 20 contained sheet metal molds 3 are stored on an inclined track 7, and are temporarily held by a chock 8.

At the end of the track 7 is located the centrifugal casting machine C, shown in detail in Fig. 1, and after the casting of the 25 ingot has been completed in this machine the carrier or drum with the ingot therein is delivered to a second inclined track 8' having a depression 9 or equivalent means 30 for arresting the travel of the carrier or drum at a required point, where a suitable plunger device 10 removes the ingot from the drum.

The carrier 1 with its contained ingot 35 mold rolls down into the centrifugal casting machine, Fig. 1, with its rails or flanges 2 resting between the flanges of four rollers 11. There is sufficient play between the flanges of these rollers 11 and the sides of 40 the flanges 2 on the drum 1 to permit longitudinal reciprocation of the carrier during the rapid rotation of the drum.

The carriers are also provided with auxiliary rails 13, one near each end of the carrier. Each of these rails 13 is engaged by a 45 pair of holding down rollers 14 for holding the drum on the rollers 11 and preventing the drum from jumping out of the machine during the rapid rotation.

50 Each pair of holding down rollers is mounted in a yoke 15 pivoted at 16 and connected at 17 to an eccentric rod 18 operated by an eccentric 19 on a shaft 20. This shaft carries both eccentrics 19, set 180° apart 55 for actuating the two yokes 15, one for each end of the drum, as illustrated.

On the shaft 20 is a worm wheel 21 driven by a worm 22 on the shaft 23 of a reversible electric motor 24.

60 On the drum 1, between the two main flanges 2 thereof, is a machined surface 25, which is capable of being engaged by one or the other of two curved arms 26. These curved arms 26 are capable of alternate engagement with the surface 25 and are oper-

ated by a reversible electric motor 27. The arms 26 serve a double purpose, to brake the drum, and to lift the drum and its contained ingot out of the machine onto the second track 8' after the metal has been cast. 70

One end of the drum is provided with a series of recesses 28 into which engage the pins 29 of the hollow clutch member 30, moved into and out of engagement with the drum by a shifting yoke or ring 31, of any 75 suitable construction. The shaft 32 of the clutch 30 is hollow and carries a spur gear 33 driven by a driving pinion 34. At the end of the shaft is a rotary blower 35 driven by a belt pulley 36.

80 After the drum is in position in the machine, a spout or runner 37 is inserted through one end. The runner is provided with the customary trap 38 into which the ladle discharges the metal. As soon as 85 the drum has been brought up to speed the metal is poured.

The detailed procedure will be as follows:—

The ingot is made by, first preparing an 90 ingot mold 3 of thin sheet metal, which may or may not be of the composition of the ingot to be formed. Usually it is not of the composition of an ingot, but of a cheaper metal. By using such a mold supported in 95 a mold carrier or drum it is possible to withdraw the ingot, with its weld connected mold immediately after solidification, from the mold carrier. This is important, in that not only is the carrier released for re-use at 100 once, but also the ingot can be transferred as hot as possible to a furnace, soaking pit, or the equivalent, for controlling the rate of cooling. The ingot molds that I have used are about one-sixteenth of an inch in thickness for hollow ingots of 18" diameter and 3" thickness of wall. The thickness of the wall of the ingot mold will vary directly with the size of the ingot, but is preferably very thin, so that in subsequent manipulation of the metal the entire ingot mold will be oxidized away. 105 110

The ingots with which I have had experience are of cylindrical and slightly conical shape, and are rotated at the high speed 115 of about 3500 peripheral feet per minute, more or less; the object being that the speed should be high enough to attain a heavy centrifugal force on the metal, sufficient to cause the elimination of segregation and 120 the slag, gas inclusions, and accidental foreign matter, and to carry them to the surface of the hollow of the ingot.

The ends *a* of the ingot molds are constructed of the same material as the body of 125 the molds, and are annular for forming the annular end walls of the ingots; the thickness of the ingot being controlled and measured by the difference between the external and internal diameter of the annulus. 130

These molds may be cylindrical, but, whatever their general shape, I prefer to have them corrugated as at 3^a and slightly conical, as in Figs. 4 and 5. The corrugations 5 may be of any desired shape, and may run longitudinally or otherwise of the mold. The mold may also be so constructed as to provide projections on its outer surface, with the object of having the mold spaced 10 at irregular distances from its carrier, (such carrier being a metal speed drum, with its interior cylindrical or conical, in which the mold is supported and rotated).

The mold is centrally spaced from the inner surface of this drum, and the intervening space may or may not be filled with an insulating material. This insulating material is preferably fine and of a sand-like character; the object being that the material 20 should have a flow similar to that of sand, in order to facilitate the withdrawal of the ingot and its adhering mold from the carrier, to allow freedom of shrinkage both longitudinally and transversely, and at the same time maintain and accommodate insulation between the mold and carrier. At 25 the same time this insulating material will produce sufficient friction between the mold and carrier to effectually prevent any slip 30 between the two during casting operations.

While I have described the mold as being spaced from the carrier, there is no objection to having corrugations, indentations or other protruding surfaces on the mold contacting with the carrier at intervals, as 35 shown at 3^b and 3^c, Figs. 6-8.

In lieu of the structure just described, the carrier may be provided with internal projections or corrugations, or I may, in some 40 cases, use both corrugations and projections; or the mold may be provided with longitudinal corrugations 3^a, and the carrier may be provided with internal circumferential corrugations 1^b, Figs. 4 and 5, so that the 45 corrugations of the one will cross the corrugations of the other; the object being to provide between the mold and carrier sufficient space to permit the insertion between the mold and carrier of some insulation material, to prevent too rapid chilling of the 50 mold and ingot.

One of the great objects attained by such a structure with a thin sheet metal mold (this mold being spaced and insulated with 55 an insulating material) is that the liquid metal never comes into contact with the insulating material; if it did, a slag might be formed, or impurities due to or contained in the insulating material might become incorporated in the metal, so that the resulting metal obtained in the ingot would not be absolutely of the same purity as the metal introduced therein. For high grade steel, 60 this is a very important consideration.

65 In order to facilitate the withdrawal of

the ingot and mold from the carrier, especially when very heavy ingots are cast, it is of advantage to make the ingot mold or the carrier, or both, conical, Figs. 4 and 5; that is to say, have an easy drawing taper. 70 The fine sand, or other insulating material having a flow like sand, greatly facilitates the withdrawal of the ingot when either cylindrical or conical shapes are used.

The ingot mold is held in position in the 75 carrier by means of adjustable clamps 6; the clamps being adjusted lengthwise of the carrier, so that it is possible with a single carrier to cast ingots any length, less than the length of the carrier.

The carrier is provided at one end, preferably at the pouring end, with a second annular head 5, spaced so as to provide a metal trough or spill-way for excess metal; the object being that sufficient metal is 85 poured until the operator sees it flow into the spill-way, by which he determines that the mold is filled. This metal in the spill-way is cropped or removed from the ingot before rolling or forging; or, in lieu of the 90 spill-way forming a part of the mold itself, I insert right next to the end of the mold a refractory spill-way 5, Fig. 9, so that when the ingot is removed from the mold the spill-way metal will separate from it. 95

When casting several ingots in a single mold, there is provided at distances apart equal to the length of the ingots, annular walls 6 of frangible, refractory material, as of fire brick, Fig. 9; or I insert in the carrier 100 short mold sections 113 spaced apart by fire brick 6, Fig. 10. The fire brick may be placed within the mold, as in Fig. 9, or it may be placed in the carrier separating short molds 113. 105

In operation, the molten metal must be poured into the rapidly rotating mold at a much faster rate than when casting solid ingots; the rate being so great as to prevent solidification starting to any appreciable extent before the pouring of the ingot is completed. 110

The practice that I have followed, and which I find especially successful is to pour molten steel into the ingot mold at the rapid 115 rate of four to five thousand pounds per minute. For the same grade of steel in a solid ingot the rate would be from one to two thousand pounds per minute; it being understood that the rates of pouring for 120 different grades of steel vary according to their composition, the temperature and the size and shape of the ingot mold. After pouring the metal into the mold and solidification is completed, I immediately remove 125 the carrier and its contained ingot and mold from the centrifugal machine, strip the carrier at once from the mold and ingot, and place the ingot and mold in an insulating material soaking pit, or heating furnace, in 130

order to prevent too rapid cooling of the ingot.

The ingot is in welded connection with its mold, and the mold, as heretofore stated, 5 is preferably of such thickness that in any subsequent rolling or forging operation, as is customary with steels, the ingot mold will be completely oxidized, leaving an ingot of pure material of the composition poured. 10 These ingots are especially free from cracks, blow holes, slag inclusions, and are of finer crystalline grain than is usually found in cast metal ingots.

With 18" diameter ingots made by me, 15 the peripheral speed is so great that the pressure on the metal at the external surface of the ingot is in the neighborhood of 30 pounds per square inch, and the pressure at the internal surface of such an ingot is 20 in the neighborhood of 20 pounds per square inch, the thickness of the ingot walls being about three and one-half inches. These pressures can be accurately determined from the known speed and diameter of the mold 25 and container. As the diameter of the ingot increases, the peripheral pressure will increase and the speed of rotation may then be appreciably decreased. These pressures are sufficiently great to force toward the 30 central inner surface any impurities, slags or gases, that may be in the metal.

In addition to the centrifugal force due to rapid rotation of the ingot, I impart a longitudinal reciprocation, and this longitudinal reciprocation or agitation assists in rapidly flowing the metal over the entire surface of the mold and prevents the formation of coarse columnar crystals, normal to the surface, as ordinarily found in vertically 40 cast solid ingots.

In order to facilitate rapid solidification, I inject, by means of blower 35, through the center of the hollow ingot immediately after pouring, a current of air, to aid the solidification of the metal throughout its thickness 45 as rapidly as possible, and also to control the rate of cooling of the ingot, in proportion to the thickness; the rate of cooling being controlled by the volume and pressure 50 of the air supply.

The rate of solidification of the ingot is also controlled by increasing or decreasing the space between the mold and the carrier, thereby varying the thickness of the insulating material between the mold and the carrier, and, where no solid insulating material is contained between the mold and its carrier, the air trapped between the mold and carrier acts in the same manner.

60 The solidification is controlled so as to arrest segregation under the casting conditions and according to the nature of the metal being cast.

I claim—

65 1. The method of casting hollow steel in-

gots, which comprises pouring molten steel into a sheet metal mold at a temperature sufficient to cause the welding of the metal and mold, and while said mold is rotated to impart centrifugal action to the metal 70 sufficient to obtain immediate distribution of the metal throughout the mold.

2. The method of casting hollow ingots, which comprises pouring molten metal into a mold maintained in rotation and longitudinal reciprocation. 75

3. The method of casting hollow ingots, which comprises pouring molten metal into an insulated metal container maintained in rotation sufficient to impart centrifugal action to the metal, and cause said container to become part of the ingot, and immediately removing the ingot with its adhering container from the rotating device, and then retarding its rate of cooling. 80

4. The method of casting hollow ingots, which comprises pouring molten metal into a sheet metal container having annular heads that determine the thickness of the ingot while supported on insulating material 90 and maintained in rotation sufficient to impart centrifugal action to the metal, whereby said container becomes welded to the ingot.

5. The method of casting hollow ingots, which comprises casting molten metal into 95 a rotating sheet metal container at a temperature welding the metal and container, said container being of a thickness sufficient to oxidize off during subsequent manipulation of the metal, and maintaining its speed 100 of rotation sufficient to overcome segregation.

6. The method of casting hollow ingots, which comprises casting molten steel into 105 a horizontal rotating thin metal mold having annular heads, and continuing the pouring of the metal until the metal in the mold spills through the central orifice at one end.

7. The method of casting hollow ingots, which comprises pouring molten steel into a horizontal rotating thin metal mold having annular heads, and continuing the pouring of the metal until said metal spills through the central orifice at one end, and 115 retaining the spilled metal in a compartment adjacent the end of the mold.

8. The method of casting hollow ingots, which comprises pouring molten steel into a horizontal rotating thin sheet metal mold 120 having annular heads; and continuing the pouring of the metal until said metal spills through the central orifice in one of said heads, and retaining the spilled metal in a separate separable compartment adjacent 125 the end of the ingot.

9. The method of casting hollow ingots, which comprises pouring the molten metal into a horizontal rotating thin metal mold while supporting said mold within a drum, 130

and withdrawing the integral ingot and mold as soon as solidified.

10. The method of casting hollow ingots, which comprises pouring the molten metal 5 into a horizontal, rotating thin metal mold while supporting the mold within a drum and immediately distributing the metal in the mold, said mold being sufficiently thin to be oxidized off during subsequent manipulation of the hot metal.

11. The method of casting hollow ingots, which comprises pouring the molten metal into a rapidly rotating thin sheet metal mold supported within a drum having heat insulation between it and the said drum, and controlling the rate of solidification of the metal under centrifugal action by the thickness of the said insulating material.

12. The method of casting hollow ingots, 20 which comprises pouring the molten metal into a horizontal, rapidly rotating, thin sheet metal mold in non-continuous surface contact with a speed drum, said mold being of sufficient thickness to be oxidized off in 25 subsequent manipulation of the metal.

13. The method of casting hollow ingots, which comprises pouring the molten metal into a horizontal, rapidly rotating, thin metal mold in non-continuous surface contact 30 with a speed drum; the interior space between said mold and drum containing a heat insulating material.

14. The method of casting hollow ingots, which comprises rapidly pouring the molten 35 metal into rotating thin sheet metal molds in non-continuous surface contact with a speed drum, the interior space between said drum and molds containing a dry, pulverulent, highly refractory, insulating material.

15. The method of casting hollow ingots, 40 which comprises rapidly pouring the molten steel into thin corrugated sheet metal molds supported within a heavy metal drum heat insulated therefrom, and maintained in 45 rapid rotation, removing the hot ingot immediately after solidification with its adhering mold, and controlling the rate of cooling of the ingot.

16. The method of casting hollow ingots, 50 which comprises pouring molten steel into corrugated thin sheet metal ingot molds supported within a heavy metal drum heat insulated therefrom and maintained in rapid rotation, removing the hot ingot and 55 its adhering mold immediately after solidification, and controlling the cooling of the ingot by covering it up with insulating material.

17. The method of casting hollow steel 60 ingots, which comprises rapidly pouring molten steel into a sheet metal mold sufficiently thin to oxidize off in the subsequent treatment of the steel ingot, said mold being rotated at a speed sufficient to instantly distribute the steel throughout the mold and

controlling the character of the steel by controlling the rate of solidification by a current of air through the interior of the mold and ingot.

18. The method of casting hollow steel 70 ingots, which comprises rapidly pouring molten steel into a sheet metal mold while in rapid rotation, controlling the character of the steel by controlling the rate of solidification of the ingot both from the exterior and 75 from the interior.

19. The method of casting hollow steel ingots, which comprises pouring molten steel into a sheet metal mold while in rapid rotation at a speed sufficient to cause an instantaneous distribution of the metal throughout the mold, and controlling the character of the metal by external insulation of the mold and the passage of a gaseous medium through the ingot and mold.

20. The method of casting hollow ingots, which comprises pouring molten metal into a rapidly rotating sheet metal mold and controlling the rate of solidification of the ingot by external insulation and internal current 85 of gaseous medium, the temperature of the metal being sufficient to weld to said mold.

21. The method of casting hollow ingots, which comprises pouring molten metal into a rapidly rotating horizontal ingot mold 90 and imparting a longitudinal reciprocation to said mold while directing a cooling medium into the interior of the ingot.

22. A sheet metal ingot mold whose exterior surface has elevations and depressions 100 and is in welded connection with the ingot.

23. The method of casting hollow steel ingots, which comprises pouring steel into a rotating ingot mold in excess of the quantity required to fill the mold, thereby imparting centrifugal pressure to the metal 105 during solidification and washing from the interior of the hollow ingot any impurities forced to the interior surface by centrifugal action, by the excess metal at the end of the 110 pouring operation.

24. The method of making hollow steel ingots, which comprises pouring molten steel into direct contact with a rapidly rotating sheet metal mold having transversely 115 arranged annular partitions, and separating the ingots at the partitions.

25. The method of making hollow ingots, which comprises pouring molten metal into a rapidly rotating sheet metal mold having 120 transversely arranged friable annular partitions, and separating the ingots at the partitions.

26. The method of making hollow steel ingots which comprises pouring molten steel 125 into direct contact with the interior of a sheet metal mold rotating at a speed sufficient to impart centrifugal force to the steel when poured, separating the metal into ingots by annular partitions, the character of 130

the steel being controlled by controlling the time of solidification of the metal by a dry comminuted insulating material.

27. The method of making hollow ingots, 5 which comprises supporting a corrugated sheet metal mold having annular heads within an interiorly corrugated speed drum, corrugations of the mold and drum crossing one another, the interspace between the mold 10 and drum containing a loose insulating material capable of yielding to expansion of the mold, rotating said mold and drum at a

speed sufficient to impart centrifugal force to the contents of the mold, and simultaneously longitudinally reciprocating the drum, 15 pouring molten metal into direct contact with the interior of the drum until some of the metal spills from the mold, and collecting the spilled metal in a separate compartment in the drum adjacent the mold. 20

In testimony that I claim the foregoing as my invention I have signed my name hereto.

FRANK D. CARNEY.
